United States Patent

Des. 236,654
Patented Sept. 2, 1975

236,654

COMBINED REFRIGERATOR CABINET AND ICE, JUICE, AND WATER DISPENSER

Ronald E. Meyer, Troy, Mich., assignor to General
Motors Corporation, Detroit, Mich.

Filed Aug. 26, 1974, Ser. No. 500,579

Term of patent 14 years

Int. Cl. D15—07

U.S. Cl. D67—3 R

Fig. 1

FIG. 1 is a perspective view of a combined refrigerator cabinet and ice, juice, and water dispenser embodying my new design, the side not shown is the same as the side shown and the rear is plain and unornamented.

FIG. 2 is a perspective view thereof with the sliding panel in the lower compartment shown in its open position wherein the dispensing service area is visible.

I claim:

The ornamental design for a combined refrigerator cabinet and ice, juice, and water dispenser, as shown and described.
